UNITED STATES PATENT OFFICE.

BRUNO VON BÜLTZINGSLÖWEN AND MENDEL HOWARD, OF NEW YORK, N. Y.;
SAID VON BÜLTZINGSLÖWEN ASSIGNOR TO SAID HOWARD.

BROOCH-PIN.

SPECIFICATION forming part of Letters Patent No. 402,701, dated May 7, 1889.

Application filed October 11, 1888, Serial No. 287,832. (No model.)

To all whom it may concern:

Be it known that we, BRUNO VON BÜLTZINGSLÖWEN, a subject of the Emperor of Germany, and MENDEL HOWARD, a citizen 5 of the United States, both residing at the city of New York, county of New York, and State of New York, have invented a new and useful Improvement in Brooch-Pins, of which the following is a specification.

10 The object of the invention is to produce an improved brooch-pin which can be easily attached to and detached from the garments of the wearer.

15 The nature of the invention consists in the details of combination and construction, substantially as illustrated in the accompanying drawings, hereinafter described, and subsequently pointed out in the claim.

20 Figure 1 is a perspective view of the back part of a brooch with our invention attached. Figs. 2 and 3 are sectional views of different modifications of the mounting-plate of the same. Fig. 4 is a plan view of the back of a brooch with a part of our invention attached, but without the needles. Fig. 5 is an edge view of the same with the needles pressed in. Fig. 6 is a sectional view of the same with the needles pressed in. Fig. 7 is a sectional view of the same with the needles drawn out. 25 Fig. 8 is a back view of another modification of our invention, but without the needles. Fig. 9 is an edge view of the same with the needles pressed in. Fig. 10 is a sectional view of the same. Fig. 11 is a sectional view 30 of another modification of our invention. Fig. 12 is a detail view of the needles. Fig. 13 is a partly-sectional view of still another modification of our invention.

35 The brooch is formed so that a tube, C, extends across the back. This may either be swaged in the mounting-plate A, as illustrated in Figs. 1, 2, and 3, or fastened thereon. This tube C may be formed so as to stand on either side of the mounting-plate, as illustrated in Figs. 2 and 3; or this tube may be fastened to the mounting-plate with clips, as illustrated in Fig. 4, or with a bar, as illustrated in Fig. 8.

40 In every case ears (designated by B and B') are formed upon or mounted on the mount-

ing-plate or the tube. In these are two holes, g and l. The holes l are opposite the axis of the tube C, at each end thereof, and the holes g are a little above the said tube, at the ends thereof.

45 In Fig. 12 is illustrated the needle of this brooch. It is made of wire of suitable thickness bent with an eye at b and two nearly parallel arms, n and n'. The arm n is curved a little to the arm n' and has a sharp point. 50 The arm n passes through the hole g and over the tube C. The arm n' passes through the hole l and into the tube C. Within the tube C is a helical spring designated in the different figures as f, f', and f''. In Figs. 6 55 and 7 this spring is designated by f and illustrated as being coiled around the arm n' of the needle and as resting with one end on the pin-head end of the arm n' and the other end upon the ear B. In Figs. 10, 11, and 13 60 this spring (designated by f' and f'') is illustrated as being between the ends of the arms n' and attached to them. In Fig. 13 this is illustrated as being accomplished by means of 65 rings on the ends of the said arms, which 70 rings are designated by e'. In this case also the tendency of the spring is to constantly 75 draw the pins in, so that they will, when free, be constantly held in.

75 To use this brooch, the back side thereof is 80 placed against the garment to which it is to be attached. Then the operator, taking hold of the eyes b, draws out the needles, and as he presses the brooch gently against the garment lets the needles go. Immediately the 85 needles spring back into their original position, and the arms n, running into the garment, hold the brooch firmly in position. By drawing out the needles, as before described, the brooch is released from the garment. 90

95 Except as herein described, this brooch is constructed and used in the common and well-known way.

What we claim as our invention, and desire to secure by Letters Patent, is—

95 The combination, with the mounting-plate of a brooch, a tube upon and extending across said mounting-plate parallel thereto, and ears upon said mounting-plate at either end of said tube, of needles having two arms, 100

substantially as specified, two of said arms passing through said ears and into said tube, one on either side of said brooch, the other arms of said needles passing through said 5 ears, one on either side of said brooch, outside of said tube, extending toward the middle thereof and nearly parallel thereto, and a spring within said tube, so connected with said needles that it draws said needles 10 inward toward the middle of said tube, all

substantially as and for the purpose set forth.

In witness whereof we hereunto set our hands in presence of two witnesses.

BRUNO VON BÜLTZINGSLÖWEN.
MENDEL HOWARD.
